INDICATOR SUPPORTING ARM FOR
PRECISION TOOLS

Arthur Beaupre, Chicago, Ill.

Application January 4, 1945, Serial No. 571,246

7 Claims. (Cl. 248—1)

1

This invention relates, in general, to precision tools for indicating or measuring the various angles of the outside or inside of an object or pattern, and other surfaces which are difficult to reach in making such measurements or indications, for the purpose of duplicating or reproducing such object. More particularly, the invention is concerned with an improved telescoping universally adjustable arm or bracket for supporting the indicator, whereby the indicator may be placed in a position to contact or measure the angle or curvature of any surface, and maintained at such angular adjustment.

A further object is to provide an improved supporting arm or bracket of this character, which will be of a simple, durable and light construction, easily manipulated, effective and efficient in operation, and which, when not in use, may be compactly arranged for storage or transportation purposes.

To the attainment of these ends and the accomplishment of other new and useful objects as will appear, the invention consists in the features of novelty in substantially the construction, combination and arrangement of the several parts, hereinafter more fully described and claimed, and shown in the accompanying drawing illustrating this invention, in which

Fig. 1 is a view, partly in elevation, partly in section, and partly broken away, of an arm of this character, constructed in accordance with the principles of this invention.

Figs. 2 and 3 are detail perspective views of elements of the arm.

Fig. 4 is a detail perspective view of one end of the body portion of one of the arm sections.

Fig. 5 is a view, partly in longitudinal section, and partly in elevation, of another form of element of the arm.

Fig. 6 is a detail sectional view taken on line 6—6, Fig. 5.

Referring more particularly to the drawing, the arm consists, essentially, of a section 10, which is tubular and may be constructed of any suitable material, and may be of any desired size and configuration. The ends of the section 10 are split, as at 11, and the split portions preferably tapered, as at 12. Secured to each end of the section 10, in any suitable manner, is a collar 13 which is provided with peripheral threads 14.

2

Co-operating with this collar is a chuck member 15 which is provided with internal threads to engage and co-operate with the threads 14 on the collar 13. The chuck member is adapted to be sleeved over the end of the section 10, so as to engage the inclined portion 12 of the section 10 and force the end of the section into gripping relation with a ball or circular member 16 on the end of a member 17.

5 This element 16 is telescoped into the section 10, and, being circular, will be clamped to the section 10 by the chuck 15, the globular end 16 of the section 17 permitting these two sections to be universally adjusted, one with respect to the other.

15 If desired, the end 16 may be formed integrally with the section 17, or may be provided with a reduced portion 18 adapted to be telescoped into a recess 19 in the section 17, and secured in any suitable manner. Both ends of the section 10 are preferably of a similar construction.

20 The numeral 20 designates another section of the arm, which is preferably formed in the same manner as the section 17, and may be tubular. This section 20 is of a cross-sectional configuration, to conform to and telescope within the section 19, and is provided with a globular end 21, similar to the end 16 of the section 17. Each of the sections 17 and 20 is adapted to telescope for a considerable distance into the section 10, the

25 section 20 as shown in Fig. 1, being thus telescoped, so as to vary the overall length of the assembled sections 20, 10 and 17. At the same time, the globular end 21 of the section 20 may be secured to the section 10 in the same manner as the end 16 of the section 17, so as to permit

30 of angular adjustment of one with respect to the other.

If desired, the collar 13 and the chuck 15 may be provided, respectively, with flattened surfaces 22—23 for the reception of a tool or implement to hold these parts while they are being relatively adjusted. Another section 24, similar in construction to the section 20, may be attached to the section 20 in a similar manner, and at the 35 end of the section 24 is arranged a similar chuck 15, whereby an indicator supporting section 26 may be similarly secured to and adjusted with respect to the section 24.

40 In use, the section 17 is clamped or secured 50 to a suitable machine, such as a height gauge

machine, and it will be manifest that by adjusting the sections of the arm, one with respect to the other, the position of the indicator which is supported by the section 26 may be varied. It will also be manifest that the length of the arm may be varied by adjusting any one or more of the sections longitudinally, one with respect to the other.

In Fig. 5, there is shown a modified form of one of the sections, by means of the use of which the length of the arm may be varied. This form may be used in addition to the form shown in Fig. 1, or may be substituted for the section 10. The modified form of section embodies a tubular member 27 which is split at one end, as at 28, to form a resilient portion. Telescoped over, and secured to the tubular member, is a collar 29 which is provided with external screw threads 30. This collar may be secured to the member 27 in any suitable manner, such as by means of screws 31. To the other end of the tubular member 27 is secured a collar 32, and the tubular member 27 is provided with slots 33—34 which are opposed to each other.

Supported by the collar 32 and also by the collar 29, is a sleeve 35 which is of an internal diameter considerably greater than the external diameter of the tubular member 27, and this sleeve 35 is provided with internal screw threads 36. Disposed within the space 37, between the periphery of the member 27 and the sleeve 35, is a nut or collar 38 that is provided with external screw threads 39 that engage and co-operate with the threads 36.

Telescoping into the tubular member 27 from one end, is an arm section 40 which may be tubular or solid, and fits within the tubular member 27. This section 40 is secured to the nut or collar 38 in any suitable manner, preferably by means of a pin or fastening device 41 that passes transversely through the nut or collar 38, and also through the section 40, the pin also passing through the slots 33—34, so that the element 40 will be moved longitudinally with respect to the tubular member 27 when the sleeve 35 is rotated, this sleeve being rotatably supported by means of the collars 29—32.

A globular extremity 42 is also provided on the section 40. The globular end 16 on the section 11 is adapted to be telescoped into the split end of the member 27, and clamped by means of a chuck member 43, similar to the chuck member 15. If desired, and in order to insure the gripping and holding of the globular end 16 of any of the sections, the gripping jaws of the section with which it is telescoped may be provided with a recess 44.

With this construction, it will be manifest that a universal adjustment may be obtained between the various sections of the supporting arm, and at the same time the length of the arm may be varied by telescoping the proximate ends of adjacent sections for the desired extent into one another.

While the preferred forms of the invention have been herein shown and described, it is to be understood that various changes may be made in the details of construction and in the combination and arrangement of the several parts, within the scope of the claims, without departing from the spirit of this invention.

What is claimed as new is:

1. An indicator supporting arm for a precision instrument, embodying a plurality of sections one of which telescopes into another, means connect-

ing the telescoping portions of adjacent sections for relative angular adjustment, means whereby the arm may be supported by one end, and means at the other end of the arm for supporting an indicator.

2. An indicator supporting arm for a precision instrument, embodying a plurality of sections one of which telescopes into another, means connecting the telescoping portions of adjacent sections for relative angular adjustment, means whereby the arm may be supported by one end, means at the other end of the arm for supporting an indicator, and means whereby the length of one of said sections may be varied at will, the last said means embodying a screwthreaded connection between said elements.

3. An indicator supporting arm for a precision instrument, embodying a plurality of longitudinally spaced sections, an intermediate section, the adjacent ends of proximate sections arranged in telescoping relation, said telescoping portions adapted for relative angular adjustment, and means for clamping the respective parts in any position to which they have been relatively adjusted.

4. An indicator supporting arm for a precision instrument, embodying sections arranged end to end and longitudinally spaced, the proximate ends of said sections being substantially ball-shaped, an intermediate tubular section into the ends of which the proximate ends of the adjacent sections telescope, the said ends of the said tubular section being resilient, and clamping members adapted to be sleeved over said resilient ends, whereby to clamp the adjacent said sections in any relative angular position into which they have been moved.

5. An indicator supporting arm for a precision instrument, embodying sections arranged end to end and longitudinally spaced, the proximate ends of said sections being substantially ball-shaped, an intermediate tubular section into the ends of which the proximate ends of the adjacent sections telescope, the said ends of the said tubular section being resilient, and clamping members adapted to be sleeved over said resilient ends, whereby to clamp the adjacent said sections in any relative angular position into which they have been moved, certain of said sections being also adapted for relative longitudinal adjustment and to be maintained in such relative adjusted position by the respective said clamping members.

6. An indicator arm for precision instruments, embodying a plurality of sections arranged end to end, the proximate ends of adjacent sections being connected for relative universal adjustment, one of said sections embodying telescoping elements, means adapting said elements for relative longitudinal and telescoping movements, means for maintaining said elements against relative rotation during such adjustment, means for connecting the proximate ends of adjacent arm sections for relative angular adjustment, a rotatable sleeve within which said telescoping portions are arranged, and means whereby, when said sleeve is rotated, longitudinal movement of the said telescoping portions of said elements will be effected, to vary the length of said arm.

7. An indicator arm for precision instruments, embodying a plurality of sections arranged end to end, the proximate ends of adjacent sections being connected for relative universal adjustment, one of said sections embodying telescoping elements, means adapting said elements for rel-

ative longitudinal and telescoping movements, means embodying a pin and slot connection between said telescoping elements for maintaining them against relative rotation during such adjustment, means for connecting the proximate ends of adjacent arm sections for relative angular adjustment, a rotatable sleeve within which said telescoping portions are arranged, and means whereby, when said sleeve is rotated, longitudinal movement of the said telescoping portions of said elements will be effected, to vary the length of said arm.

ARTHUR BEAUPRE.
